UNITED STATES PATENT OFFICE.

RICHARD WOOD DAVIES, OF CROYDON, NEAR SYDNEY, NEW SOUTH WALES.

BRICK-MACHINE.

SPECIFICATION forming part of Letters Patent No. 439,322, dated October 28, 1890.

Application filed July 18, 1889. Serial No. 317,954. (No model.) Patented in New South Wales September 13, 1888, No. 935.

To all whom it may concern:

Be it known that I, RICHARD WOOD DAVIES, a subject of the Queen of Great Britain, residing at Croydon, near Sydney, New South Wales, have invented certain new and useful Improvements in Brick-Machines, (for which I have received a patent in New South Wales, dated September 13, 1888, No. 935;) and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The invention relates to brick-machines in which power is applied by mechanical means —such as cams, eccentrics, and the like—actuated by any suitable motor; and it has for its object to provide means whereby the bricks may be more uniformly compacted or consolidated, whereby the danger of breakage or damage to the operative devices is greatly lessened.

In the accompanying drawings, Figure 1 is a front elevation of a brick-machine embodying my invention. Fig. 2 is a side elevation, and Fig. 3 is a top plan view. Fig. 4 is a vertical section taken on or about on line $x-x$ of Fig. 2, and Fig. 5 is a like view taken on or about on line $y-y$ of Fig. 4.

In the above-described figures of drawings like letters indicate like parts wherever such may occur.

A indicates the base or sole plate of the machine, upon which the entire structure is mounted, and from which rise two uprights or cheeks A' A'', in which are formed the bearings for the upper and lower cam or eccentric shafts C and D, respectively, the said standards or cheeks being provided with vertical slots A⁵, in which move the journals of the upper piston or cross-head E, to which is bolted the upper piston E'. The said cross-head E has formed therein on a line with the mold-boxes B an opening for the reception of a frog-mold E'', the shank of which carries an anti-friction roller E³, that is acted upon by a cam C' on the upper cam-shaft C. The said shaft C also carries two cams C² C²—one on each side of cam C'—that operate upon anti-friction rollers E⁴, mounted on the upper

cross-head E. The cams C² C² are of less diameter than the cam C', so that the latter cam will depress the frog-mold E'' in advance of the cross-head E', the prongs of said mold extending into or working in slots formed in the upper piston E', whose upper face constitutes the bottom of the opening in the cross-head E and serves to limit the downward movement of the frog-mold, the contracted upper portion of said opening, in which works the shank of said frog-mold, forming abutments that limit the upward motion of said mold. The upper cross-head E is provided at opposite ends with a journal D⁶, that projects through the slots A⁵ in the cheeks A', and to said journals is secured one end of a rod D⁵, the opposite end of which is forked and has a roller D⁷ mounted in said fork, which roller rides upon a cam D⁴, mounted on the lower shaft D. The vertically-reciprocating rods D⁵ are guided in brackets A⁶, projecting from the cheeks A'. The lower shaft D carries a cam or eccentric D⁸, that operates upon an anti-friction roller F³, mounted in bearings F² on the under side of the lower piston or cross-head F. The said shaft D also carries two eccentrics D⁹ D⁹—one on each side of eccentric D⁸—the straps or rods F⁴ of which operate in slippers F⁵ on the lower cross-head F, which is provided with two pistons F'—one for each mold-box B, of which I have shown two—the upper piston being provided with a transverse notch or recess fitting over the partition B² between the two mold-boxes. (See Fig. 4.)

For the purpose of determining the thickness of the brick to be made, I provide means for adjusting the limit of downward motion of the lower pistons F', which means consist of wedge-pieces H, that rest upon a suitable supporting-box H¹⁰, the upper face of which is inclined, as shown in Fig. 4. The wedge-pieces are adapted for adjustment under the lower cross-head F by means of a lever H', pivoted at H² to the outer end of the wedge-pieces H and fulcrumed at H³ to a bracket H⁴, depending from the delivery-table A⁸, and said lever is provided with a handle H⁷ and a spring-actuated catch H⁶, adapted to engage one or the other of the notches in a quadrant H⁵, as shown in Fig. 2. The vertical movement of the piston-head F is guided by guide pins or rods F⁶.

In order to automatically feed the material

to the mold-boxes, I provide a feed-box G, that has an extension-board G', fitting closely under the feed-hopper A⁴, that is secured to the feed-table A² of the machine. The feed-box G is connected by a link or connecting-rod G² to a radial arm or lever G³ on the power-transmitting shaft G⁴, that is adapted to revolve in bearings G⁵ and carries a pinion J² in gear with a wheel D¹⁰ on the lower shaft 10 D, the said wheel D¹⁰ being in gear with a wheel C⁸ on the upper shaft C.

An intermittently-reciprocating movement is imparted to the feed-box G through the medium of the radial arm or lever G³¹ on the shaft G⁴, said lever carrying at one end an anti-friction roller G⁶ in the path of cam-ribs or risers D² D³ on a cam-disk D', secured to the lower shaft D, the free end of the lever being maintained in a proper position relatively to the cam-ribs by a spring G¹⁶. (See Fig. 2.)

The operation of the machine is as follows: Motion being imparted to the driving-shaft I, which carries the fast and loose belt-pulleys I' I²¹, said motion is transmitted through pinion I² on shaft I to pinion J' on shaft G⁴, and through pinion J² on said shaft to the gear-wheel D¹⁰, and through the latter to the gear-wheel C⁸, thereby revolving the upper 25 and lower shafts C and D, respectively, while the lever G³¹ imparts motion to the feed-box G, which, being filled with clay, is caused to move forward over the mold-boxes, the clay being discharged into the same, while the extension-board G' will prevent the clay in hopper A⁴ from falling out at the lower end, said extension-board performing the function of a valve. As soon as the clay in the feed-box is dumped into the mold-boxes B the said 30 feed-box is returned to its normal position by the action of the levers G³ G³¹, the roller of which lever G³¹ travels then between the cam-ribs or risers D² D³. While the feed-box G is being refilled under hopper A⁴ the center 35 cam C', which, as hereinabove stated, is of greater diameter than the cams C² C², first impinges upon roller E³, thereby depressing the frog-mold E² in advance of the cross-head E and upper piston E', the said frog-mold E² having free vertical motion within certain 40 limits in said cross-head and piston. The outer cams C² now operate upon the rollers E⁴ and depress the cross-head and top piston with the frog-mold, which first makes a 45 comparatively deep impression in the clay in the mold-boxes B, after which the piston E enters the mold-boxes. Simultaneously with these movements of the upper piston and frog-mold the eccentrics D⁹, through their rods 50 F⁴ and the slippers F⁵, cause the lower cross-head F to move upwardly, the pistons F' rising within the mold-boxes, thus compressing the clay therein.

By the operations described a more uniformly-compacted brick is obtained than

would be the case otherwise, the brick being perfect and true in form and having sharp edges and angles. It will of course be understood that before the upper piston E' has reached the limit of its downward motion the frog-mold will have reached the limit of its motion in the same direction, so that when said upper piston, in conjunction with the lower pistons, applies the final pressure to the clay in the mold-boxes the cam C' will have 75 moved out of contact with the roller E³ on the frog-mold, which will remain stationary while the upper piston is still moving downward, so that when said piston reaches the limit of its downward movement the lower extremity of 80 the prongs of the frog-mold will be substantially flush with the lower face of the piston E', so as to leave the upper face of the brick smooth. The object of the primary partial compression of the clay in the molds by the 85 frog-mold E² is to drive out the major portion of the air contained in the clay, whereby the final compression is not only facilitated, but a denser and more homogeneous brick is obtained.

During the compression of the clay the center eccentric D⁸ will keep the pistons F' firmly in their mold-boxes B, and as soon as the top pressure is relieved through the cams D⁴ acting upon the rollers D⁷ at the lower end of 95 the pendent arms D⁵, secured to the upper cross-head E, the said pistons F' will move upward, also, to the level of the mold-boxes B. As the pistons F' reach the limit of their upward movement, the filled feed-box G makes 100 its traversing motion and pushes the finished bricks onto the delivery-table A³, the clay in said box falling into the mold-boxes, when the described operations will be repeated.

Having described my invention, what I claim is—

1. In a brick-machine, the combination, with the piston-head E, the piston E', secured thereto, and the frog-mold E², adapted to have independent motion within said piston-head and piston, of the mold-box B, divided into two compartments by a partition B² of the cam-shaft C, and the cams C' and C² C², said cam C' being of greater diameter than the cams C², substantially as and for the purposes set forth.

2. In a brick-machine, the combination of the shaft D, the cams or eccentrics D⁴, and the gear-wheel D¹⁰ on said shaft with the cam-shaft C, the gear-wheel C⁸ thereon, and the cross-head E, having pendent arms having bearing on the eccentrics D⁴, substantially as and for the purposes set forth.

RICHARD WOOD DAVIES.
